UNITED STATES PATENT OFFICE

LUCIUS E. FRAZIER, OF BARTLESVILLE, OKLAHOMA, ASSIGNOR TO PHILLIPS PETROLEUM COMPANY, OF BARTLESVILLE, OKLAHOMA, A CORPORATION

METHOD AND APPARATUS FOR GAUGING THE CONTENTS OF TANK CARS AND THE LIKE

Application filed February 25, 1928. Serial No. 256,958.

This invention relates to improved means for gauging the contents of receptacles, and has particular relation to the gauging of the contents of tank cars adapted to contain volatile liquids.

The primary object of this invention is the provision of improved means for gauging the contents of tank cars which are adapted to receive volatile liquids, such as liquefied petroleum gas, and which enables an accurate gauge reading of the contents of the car without removing dome covers and the like from the tank car.

A further and important object of this invention is the provision of improved means for gauging the contents of tank cars, such as class "IV—A and V" tank cars, in a practical manner which complies with statutory provisions that the cover of the car shall not be opened; the improved gauging means permitting an accurate level reading of the contents within the car without permitting any appreciable loss of the contents within the car which is under high pressure.

A further object of this invention is the provision of an improved method and apparatus for determining the liquid level within a receptacle containing liquid under pressure greater than external pressure.

Heretofore gauging of the contents of tank cars has been effected in the practical art by either gauge pole measurements or by weighing on suitable track scales. The gauge pole measurement of tank car contents involves the removal of dome covers and the like, and while this is legal in connection with the handling of certain hydrocarbons, it is not only illegal but impracticable to so measure the tank car contents where highly volatile

shipments are in transit, due to the extreme hazard and loss of material being shipped, by vaporization. The weighing of tank cars in order to determine the contents is both expensive and inconvenient, as well as im-

possible at many places. In the weighing of tank cars to ascertain their contents, a small error very often seriously affects the volume of shipment in the tank car, to the loss of the shipper, in cases of reduced volume, or in-

increased volume. Other methods consist of providing dome covers with sight holes and the like, which method of ascertaining tank car contents is highly inaccurate. With the present invention I overcome many of the difficulties heretofore encountered in the accurate gauging of the highly volatile contents of tank cars, such as are adaptable for shipping liquefied petroleum gas and the like. The rapid and accurate determination of the volume in the tank car is obtained broadly by lowering from externally of the receptacle compartment, an open tube of known length or dimensions, into the tank compartment, above the liquid level, until a lower opening immerses into the top of the liquid, so that the liquid will be pressure forced to externally of the tank car, into a visible relation. This is done without the removal of dome covers and the like, and thus many of the losses and hazards to life and property are eliminated.

Other objects and advantages of this invention will be apparent during the course of the following detailed description.

In the accompanying drawings, forming a part of this specification, and wherein similar reference characters designate corresponding parts throughout the several views.

Figure 1 is a fragmentary vertical sectional view taken through the valve and gauge dome of a tank car adapted to receive highly volatile liquids having a tendency to vaporize at atmospheric pressures, showing the improved gauging device in position upon the tank dome cover plate.

Figure 2 is a view, partly in section, taken horizontally across the dome housing substantially on the line 2—2 of Figure 1, showing in plan view the relief valve; the eduction valves; vapor vent valve, and the improved liquid level gauging device.

Figure 3 is a horizontal sectional view taken through the upper portion of the improved gauging device.

Figure 4 is a vertical sectional view showing details of the improved gauging device and its mounting and operating means.

taken through the upper portion of the improved gauging device, showing means for raising and lowering the gauge tube.

Figure 6 is a vertical sectional view of details of the improved gauging device, taken in vertical plane at a 90° angle with respect to the section of Figure 4.

Figure 7 is a fragmentary vertical sectional view taken through the improved gauging tube.

Figure 8 is a side elevation showing the graduated gauge tube as used with this invention.

Figure 9 is a fragmentary view, partly in section, showing means for venting of pressure from within the housing which covers the gauge device, prior to entire removal of the housing.

Figure 10 is a plan view of the gauging device cover or housing.

In the drawings, wherein for the purpose of illustration is shown only a preferred embodiment of my invention, the letter A may generally designate a receptacle, such as a tank car, having a dome construction B included as a part thereof, of the usual type adapted to be installed upon tank cars carrying highly volatile liquids, and upon which dome construction B a conventional relief valve C may be supported, together with a vapor vent valve D and eduction valves E and F. The improved gauging device G is associated with the dome construction B, in a new and novel relation for the gauging of the level and determination of the volumetric contents of the tank car after an improved method.

The tank car A includes the ordinary cylindrical inner shell 15, disposed on a horizontal axis, surrounded in spaced relation by an outer jacket 16, and between which insulation 17 is disposed, preferably either cork or asbestos cement. On the top of the tank car the dome header 18 is suitably welded or otherwise sealed at a joint 19; the header 18 being disposed on a vertical axis, and being relatively short, and having a passageway 19^a therethrough. The dome header 18 is annularly flanged at 20, to receive bolts 21^a, by means of which to detachably bolt the dome cover plate 21 in place; the dome cover plate 21 having an annular sealed gasket connection at 22 upon the flange 20, as shown in Figure 1. The passageway 19^a is relatively shallow, and is not intended to be used similar to the vapor dome of an ordinary petroleum tank car, since the dome structure of the tank car A is only used to receive valves and measuring accessories. A cylindrical shaped dome housing 23 is bolted at 24 upon the outer marginal portion of the dome cover plate 21, and the compartment 25 therein is adapted to receive details of the valves C, D, E and F and the gauge device G. The dome housing cover 27 is pivoted or otherwise suit-

ably connected at 28 upon the housing body 23, and is of the usual type understood in this art. It is well understood in the art that when volatile liquid contents are in the tank car, the cover plate 21 is always attached and it is impractical and illegal to remove the same. The inlet and outlet of the contents are effected thru the valves E and F, and the excess pressure relief valve C is known as the safety valve, while the valve D vents exhaustive vapors into the dome housing compartment 25 and therefrom thru an opening 30, under conditions understood in this art.

Referring to the gauging device G, the same includes a base 35 of substantially disc-shaped formation, attached by a plurality of bolt devices 36 upon the cover plate 21. The bolt devices 36 each include a shank 38 screw threaded at opposite ends, and preferably including an intermediate smooth portion for free disposal thru a passageway 39 in the base plate 35, as illustrated in Figure 6. One screw threaded shank of each of the bolt devices 36 detachably threads into a socket provided therefor in the cover plate 21, and the opposite screw threaded end thereof extends upwardly above the top surface of the base plate 35, for receiving a cap screw 40. The bolt devices 36 are eccentrically placed upon the base plate 35, and at the center of the plate 35 is provided a stuffing box 42, for slidably receiving the gauge rod or tube 44 therethrough with a leak-proof connection. The base plate 35 is of course provided with a passageway 44^a therethrough for slidably receiving the gauge tube 44, and the plate is provided with an upstanding screw threaded shank or collar 47 for detachably receiving the packing nut 48, by means of which a follower 49 may be clamped down upon packing material, to compress the latter about the gauge tube 44 which extends through the base plate 35 at opposite sides thereof.

The dome cover plate 21 is of course provided with a passageway 50 therethrough, through which the gauge tube 44 may operate to extend into the compartment of the tank car A. In order to prevent leak of contents from the tank car A, wherein the liquid is ordinarily under superatmospheric pressure, I prefer to provide an annular flange or protuberance 51, extending from the bottom surface of the plate 35, and surrounding the passageway 44^a, which is adapted to telescope into an annular groove provided inwardly of the top surface of the dome cover plate 21; suitable packing 52 being placed between the facing bottom surface of the groove and the lower edge of the annular flange 51, as shown in Figures 4 and 6 of the drawings, to provide an effective seal, when the bolts 36 clamp the base plate 35 upon the cover plate 21, in the position illustrated.

The gauge tube 44 is of novel construction, including the main tube body 60, ordinarily formed of stock material, which has disposed therein a small tube 61, preferably spot welded in place, in order that the gauging tube may have a very small passageway 62 therethrough, best suited to determine liquid levels in the tank car in accordance with the hereinafter described operation. The tube body 60 at the lower end thereof is provided with a valve casing 63, wherein a check valve 64 is positioned, normally gravity positioned upon a cross bar 65 to be unseated from the passageway 66 thru the valve casing; the valve casing 63 having a valve seat 67 facing downward, upon which the check or ball valve 64 may seat under predetermined pressure conditions to close the passageway 62 from the compartment of the tank car.

At the top of the gauge tube 44 is provided a valve device 70, including a valve casing 71, of preferably the angle type, screw threaded at 72 upon the top of the tube body 60, and having a needle valve 73 screw threaded therein, provided with a needle point 74 adapted to seat at 75 in the valve casing to close off the passageway 62 from atmospheric communication. The needle valve 73 has a handle 76 exteriorly of the valve casing, to permit its convenient adjustment, and the angle nozzle 77 is of course provided with a relatively large duct 78 therethrough, into which contents passing the needle valve seat 75 from the passageway 62 may enter to pass off exteriorly at the top of the gauging tube or device. For a purpose which will be subsequently mentioned it is preferred to provide a calibrated member 80 over the outlet end of the nozzle 77, having a fine passageway or duct 81 therethrough equal to or less than the cross area of the passageway 62. The tube body 60 is externally graduated, as shown in Figures 1 and 8 of the drawings; the same being preferably graduated in inches and $\frac{1}{8}$ -inch divisions therebetween, the graduations increasing from zero upwardly along the tube, from a location intermediate the ends, for reasons which will be subsequently apparent; the graduations continuing to the needle angle valve structures 70.

The gauge tube 44 is adaptable for vertical sliding in a line normal to the liquid level within the tank car. In order to maintain the line of movement of the gauge tube vertical within the tank car compartment, it is preferred to provide a steadyng guide tube or pipe 85, having a screw threaded connection at 86 in the cover plate so as to align the passageway of the pipe 85 with the passageway 50 thru which the gauge tube slides. The guide tube 85 preferably has a step bearing 89 in the lower portion of the tank compartment, so that the guide tube is positioned truly vertical against swaying, and may guide

the travel of the gauge tube device 44 in a true perpendicular line. In order that liquid and vapor from the tank car compartment may enter the passageway of the tube 85, it is preferred to perforate the latter at 90, therealong.

Means is provided above the base plate 35 for slidably moving the gauge tube 44. Such means preferably consists in a rack and pinion adjustment. To this end, a supporting frame or yoke 100 is provided, comprising supporting legs 101 and 102, connected at their upper ends by a cross plate 103, provided with an opening thru which the gauge rod device 44 may slide upwardly, without obstruction. The legs 101 and 102 are outwardly flanged at 107, at their lower ends, and apertured, for receiving the outwardly extending screw threaded shanks 108 of two of the diametrically opposed cap nuts 40. Nuts 109 adjust on the screw threaded shanks 108, to clamp the flanges 107 in place, and support the frame 100 in a stationary position with the legs 101 and 102 straddling the stuffing box 42.

It is preferred to adjustably clamp a rack bar to the upper portion of the gauge tube 44, and to this end a sleeve 115 receives the upper portion of the body tube 61 therethrough; the sleeve 115 being split at its upper and lower ends 116 and 117^a respectively; the sleeve 115 at opposite sides of these splits being provided with ears for receiving bolts 117 by means of which to draw the split sleeve at its upper and lower ends into a clamping engagement with the gauge tube device 44 which extends therethrough. Integral with the sleeve 115 is the rack 120, comprising teeth arranged vertically along the split sleeve 115. A shaft 125 is rotatably supported at its opposite ends in the frame legs 101 and 102, as shown in Figures 4 and 6 of the drawings; the shaft 125 having a pinion 126 keyed therewith in a meshing relation with the rack bar 120. A crank 127 is rigid on the shaft 125, at the outer side of the leg 102, and the crank 127 preferably has a collapsible handle 128 thereon by means of which to facilitate rotation of the shaft 125 to the crank 127.

A substantially cylindrical shaped housing 140 is provided for enclosing the details of the gauging device which are positioned externally upon the base plate 35. It includes a cylindrical body portion 141 having a top wall 142 provided with a reduced hollow polygonal cap 144 preferably rigid or integral therewith, for wrench engaging purposes. The body 141 is screw threaded and open at its lower end for screw threading at 145 upon the peripherally screw threaded base plate 35, as shown in Figures 4, 6 and 9 of the drawings. The base plate 35 is provided with an annular flange 146 annularly projecting beyond the screw threaded con-

- nection 145, the same being of less thickness than the thickness of the plate 35 and providing a seat for supporting a gasket 147, upon which the lower edge of the housing 140 may seat in a sealing relation, to prevent escape of vapor contents from the compartment within the housing 140 past the connection of the said housing with the base plate 35, as is perfectly apparent. Some of the 5 connections of the details of the gauging device may be leaking, and hence the sealed housing construction 140 has been provided to prevent escape of the high volatile contents of the tank car by vaporization. Inasmuch as the pressure in the housing compartment is superatmospheric, it is preferred that some means be provided to vent the same to atmospheric pressure prior to entire removal of the housing 140. To this end I 10 prefer to provide right angled shaped ducts 150, in the base plate 35, having outlets on the top surface thereof and at the screw threaded periphery thereof, which are unseated in the course of unscrewing of the housing or cap 140, and of course will release the pressure from within the housing prior to entire removal thereof from the base plate 35, as can readily be understood from the arrangement of parts in Figure 9.
- 15 In order to provide a further seal against escape of contents of the housing when closed, the cap nuts 40 may be clamped against suitable lead washers 160, to prevent leak of pressure past the bolts 38.
- 20 The scale upon the gauge tube 44 is so calibrated with respect to the dimensions of the tank car that when the open lower end of the gauge tube 44 is at the top of the tank car where the maximum level of liquid is to be placed, such as at the point 160^a 25 shown in Figure 1, the zero reading of the scale will appear opposite the pointer 170, shown in Figures 3 and 6 of the drawings, as located on the top plate or portion 103 of the frame 100. When in this position the gauge device indicates that there is no outage. The gauge tube 44 is of course raised and lowered through the rack and pinion arrangement carried by the frame 100, in a 30 manner which is obvious from the above description.
- 25 If the tank car is to be filled, the housing 140 is of course removed from the base plate, and the handle 128 swung downwardly into position, and the gauge tube 44 moved upwardly through the stuffing box 42 by turning the crank 127, which rotates the pinion 126 and elevates the rack 120, to move the gauge rod 44 upwardly. The operation is 35 repeated until the zero mark appears opposite the pointer 170. The tank is then filled by applying the line connection with one or the other of the eduction valves E or F, and when the level of the liquid reaches the lower 40 open end of the gauge tube 44, the liquid will be forced upwardly through the restricted passageway 62, inasmuch as the air space or vapor space in the tank car A is under superatmospheric pressure; the liquid being forced upwardly thru the gauge tube, and inasmuch as the needle valve 76 is slightly raised above its seat the liquid will be forced into the nozzle 77, and visibly appear through the opening 81, and after which the needle valve is closed and the gauge tube lowered and the 45 housing 140 applied, for the tank car has been filled with its volatile liquid content to the maximum level. The gauge tube 44 is provided of the heavy walled small bore type, so that the passageway therethrough is of 50 small volumetric capacity, which consequently diminishes the time lag factor in making observations. The bore of the passageway 62, by way of example only, may range from $\frac{1}{2}$ nd of an inch in diameter to a quarter of an inch. It had been previously found that when opening the needle valve 73 to a certain extent, the pressure within the tank car forced the contents of the tank car with too great a velocity past the needle valve seat, 55 sometimes freezing the opening due to lowering of temperature incident to expansion. Therefore, the cap 80 was placed so as to provide a small duct 81, which may range from .0135 to .125 inches in diameter, so as to prevent this expansion at the needle valve seat.
- 60 The vapor pressure on the volatile liquid in the car, at normal temperatures of from 30° to 120° F. is superatmospheric, ranging 65 from atmospheric pressure to 200 pounds pressure per sq. inch.
- 65 In order to determine the outage in the tank car, it is merely necessary to lower the gauge tube 44 by its operating means, and the needle valve 76 being open, it is apparent that when the lower open end of the tube 44 reaches the liquid level, the liquid will be pressure forced quickly through the small 70 diameter duct or passageway of the gauge tube, and inform the observer exteriorly of the tank car that the top level of the volatile liquid has been reached. The reading on the gauge rod scale may then be taken opposite the pointer 170, which indicates the 75 outage in inches or the like. From this the volumetric contents of the tank car can be readily calculated, if the scale is not graduated to immediately determine the contents.
- 80 It is entirely practical to use the improved gauge tube in a simpler manner than that shown in the drawings, by providing merely a sealed connection of the tube with the tank, thru which it may be slid into and out of the tank without the intervention of rack and bar and other mechanical expedients. The check valve at the bottom of the gauge tube has been provided to increase the safety factor, and prevent escape of the volatile 85 contents of the car through the gauge tube, 90

in event of serious accident to the tank car, such as if the superstructure of the improved device is torn away by wreckage. This check valve may be dispensed with if found desirable.

6 It is apparent from the foregoing that a method and improved apparatus have been provided for accurately gauging the liquid contents of tank cars receiving highly volatile liquids, in a manner which is both practical and legal. Among other advantages, there are four which are important in relation to the shipment of volatile liquids, such as liquefied gases, directly obtainable by use of the improved gauging apparatus, as follows:—

10 1. The improved gauging device enables the shipper to load the maximum permissible volume of volatile liquid.

15 2. It enables the carrier to definitely determine if the confinement of volatile liquids is safe for shipment.

20 3. It provides the sellers and buyers of volatile liquids with means for accurately determining the basis for their transaction.

25 4. It widens the market for volatile liquids by removing the necessity for use of expensive track scales and other measuring accessories.

30 While the drawings portray the present invention in a good practical form, it is to be understood that the proportions and materials of the device as set forth are not a vital embodiment of the invention; that changes may be made from time to time to conform with the rulings of those agencies controlling common carriers or other reasons; and that various changes in the shape, and arrangement of parts may be made to the form of invention without departing from the 35 spirit of the same or the scope of the claims.

40 I claim:

1. In a tank car gauging device the combination with a tank car, of a hollow tube, means mounting the tube for upright slidable movement in the tank car for partial insertion thereinto to various degrees, a housing externally on the tank car for enclosing the exposed portion of the tube, means to seal the compartment in the housing against release 45 of pressure therefrom, said housing and said last mentioned means cooperating in structure to provide vent ducts which open to release pressure from within the housing during removal of the latter and prior to entire 50 removal thereof.

55 2. In a tank car gauging device the combination with a tank car, of a tube slidable upon the tank car in a substantially vertical line from the upper part of the tank car, a 60 normally open check valve in the lower end of said tube adapted to close under abnormal forces placed thereon, and a manually operated valve on the tube externally of the tank car.

65 3. In a gauging device for tank cars the

combination with a tank car having a compartment therein, a guide tube connected with the tank car in a stable vertical position within the compartment of the tank car, a gauge tube slidable within said guide tube from externally of the tank car and opening in said guide tube, the guide tube having openings therein to the compartment of the tank car to permit entry of the contents of the tank car into the guide tube into contact with the gauge tube, means providing a pressure sealed sliding connection of the gauge tube relatively to the tank car to permit movement of the gauge tube into or out of the tank car guide tube, a rack on the gauge tube externally of the tank car compartment, a pinion meshing with the rack, means rotatably supporting the pinion so that upon rotation of the latter the rack moves longitudinally for elevating and lowering said gauge tube, and a valve on the gauge tube for regulating escape of fluids from the tank.

70 4. As an article of manufacture a gauge tube of the class described comprising an elongated upright tubular body having a passageway therethrough, adjustable release valve means at the upper portion of the tube for controlling the opening of the passageway, said tube externally therealong having scale graduations, and a normally open check valve at the lower portion of the tube being gravity controlled to normally maintain an open position when the rod is substantially vertically positioned and adapted to close when the liquid velocity thru the tube exceeds a predetermined limit.

75 5. As an article of manufacture a gauge tube for registering liquid levels and liquid depths comprising an upright elongated thick walled tube having a fine bore passageway longitudinally therethrough, the tube externally therealong having a scale, a normally open gravity operated check valve at the lower end of the tube, and an adjustable needle valve for regulating the opening of the passageway at the upper end of the tube.

80 6. As an article of manufacture a gauge tube for testing liquid levels of pressure liquids within tank cars the combination of an elongated upright graduated tube having a passageway therethrough, valve means at the upper end of the tube for regulating the opening of the passageway, the valve means having an outlet nozzle, and a device on the nozzle having a calibrated opening for preventing too fast expansion of fluids as they enter the passageway and pass said valve.

85 7. In a gauge tube an elongated upright tubular graduated body having a fine bore passageway therethrough, a valve including a casing at the upper end of the tube and a needle adjustable in the casing for regulating the opening of the passageway of the tube, said valve casing having an outlet, and a device attachable over the outlet opening of the 90

- valve casing having a calibrated opening sufficiently small so as to prevent freezing of expanding pressure operated fluids passing through the body at the needle when the latter is open.
- 5 8. A gauge device for determining the amount of liquid within receptacles and tank cars and the like comprising a base carried by the top of said tank car and having a stuffing 10 box thereon, a graduated upright tube slideable relative to said base in the stuffing box, means on the base and the tube for positive sliding of the tube with respect to the base, and a housing having a releasable sealed connection with the base for enclosing in a sealed 15 relation the last mentioned means and the end of the tube associated therewith.
9. A gauge device for determining the amount of liquid within receptacles and tank 20 cars and the like comprising a base carried by the top of said tank car and having a stuffing box thereon, a graduated upright tube slideable relative to said base in the stuffing box, means on the base and the tube for positive 25 sliding of the tube with respect to the base, a housing having a releasable sealed connection with the base for enclosing in a sealed relation the last mentioned means and the end of the tube associated therewith, and 30 means carried by the base for attaching the base in a sealed connection with a tank car.
10. In combination with a tank car having a passageway through the top wall, a base plate, means detachably connecting the base 35 plate in a sealed connection with the tank car, the base plate having a stuffing box thereon provided with a passageway aligning with the passageway of the tank car, a graduated tube slideable in the stuffing box through the 40 passageway thereof and through the passageway of the tank car so as to be extended into the tank car, a frame carried by the base, a rack, means mounting the rack upon the upper portion of the gauge tube for longitudinal 45 adjustment thereon, a crank shaft rotatable on the frame having a pinion meshing with said rack, and a release valve carried by the upper portion of the gauge tube for opening the latter to the atmosphere.
- 50 11. In combination with a tank car having a passageway through the top wall, a base plate, means detachably connecting the base plate in a sealed connection with the tank car, the base plate having a stuffing box thereon provided with a passageway aligning with the passageway of the tank car, a graduated tube slideable in the stuffing box through the 55 passageway thereof and through the passageway of the tank car so as to be extended into the tank car, a frame carried by the base, a rack, means mounting the rack upon the upper portion of the gauge tube for longitudinal adjustment thereon, a crank shaft rotatable on the frame having a pinion meshing 60 with said rack, a release valve carried by the
- upper portion of the gauge tube for opening the latter to the atmosphere, and a housing attachable with the base in a sealed connection to house the stuffing box, frame, rack and pinion and upper portion of the gauge 70 rod therein in a sealed compartment.
12. In a tank car gauging device the combination with a tank car, of a tube movable in an upright relation upon the tank car in a sealed connection therewith so that the tube 75 may extend to various degrees into the tank car, external valve means for regulating the passageway in the tube, and a check valve in the tube normally open by gravity to permit tank car fluids to pass through the tube to the valve means first mentioned, and adapted to operate incident to abnormal pressures to close said passageway.
13. In a tank car gauging device the combination with a tank car, of a tube movable 80 on the tank car for partial insertion therewith into various degrees, a housing externally on the top of the tank car for enclosing the exposed portion of the tube, said housing having a compartment with a lower open end and otherwise sealed, the tank car having a portion in screw threaded engagement with the lower open end of the housing, the housing and said portion having associated port means which will permit release of pressures 85 from within the housing to the atmosphere when the housing is unscrewed on the plate to a predetermined degree and prior to entire removal of the housing from said plate.
14. In combination a tank for receiving a high pressure fluid under pressure greater than atmospheric, a gauge tube, means slidably mounting the gauge tube upon the tank 90 in pressure sealed relation therein for movement to various degrees into the tank in line normal to the level of pressure liquids contained in the tank, the tube being open in the tank, an escape valve carried upon the tube externally of the tank for regulating escape of pressure fluid from within the tank 95 to the atmosphere, and calibrated vent means from within the tank to the atmosphere, and calibrated vent means for regulating escape of the pressure fluid in an expansion preventing relation at the location where the escape valve regulates the exit of the pressure fluid from the passageway of said tube, to prevent freezing adjacent the escape valve when the latter is open 100 in said tube.
15. In a tank car gauging device, the combination with a tank car, of a tube movable 105 in an upright relation upon the tank car for partial insertion therewith into various degrees, said tank car surrounding said tube having externally thereon a raised externally screw threaded portion, a housing detachably connected upon said screw threaded raised portion and housing the end of the tube therein which is external of the tank, gasket means against which the housing 110 clamps to seal the compartment of the hous- 115
- 120
- 125
- 130

ing from the atmosphere, said raised portion having ducts opening thereupon within the housing compartment and at their opposite ends opening on the screw threaded portion 5 of the housing at the housing side of said gasket means whereby to be opened when the housing is partially unscrewed from the raised portion to unseal the housing compartment from the gasket means but prior to entire disconnection of the housing from the screw threads of said raised portion.

16. In an outage gauge for tanks the combination of a tank, a graduated tube, means slidably mounting the tube on the top of the 15 tank in pressure sealed relation therewith, the tube being open within the tank and extending externally of the tank, escape valve means on the tube externally of the tank for regulating escape of pressure and fluids from 20 within the tank, a releasably sealed housing on the tank externally thereof capping the external end of the tube therein, and a dome upon the tank receiving the said housing therein, said dome having closure means 25 thereupon of a size suitable for access to and removal of the sealed housing.

17. In gauge apparatus for determining the amount of liquid within tank cars and the like, the combination of a tank car, a 30 stuffing box mounted on the top thereof, a hollow slideable gauge tube slideable in an upright relation through said stuffing box so that the tube may be inserted to various depths in the tank car, said tube being open 35 at its lower end in the tank car and being of a length so that the same may be substantially entirely inserted within the tank car with a short upper end projecting above the top of the tank car, valve means on the upper 40 portion of the tube externally of the tank for opening or closing the tube, means carried by the tank externally thereupon to positively withdraw the tube or lower it into the tank car, and a housing carried by the top 45 of the tank car for releasably sealing therein the upper portion of the gauge tube and said last mentioned means, when the latter is substantially completely lowered into the tank car, said housing having a sealed connection 50 with the top of the tank car surrounding said stuffing box to prevent leakage of tank car contents from said housing.

18. In a gauge device the combination of a tank, a stuffing box carried at the top of the 55 tank, an upright hollow gauge tube slideable in a sealed relation through said stuffing box and of a length to permit the same to be slid into the tank for substantially its entire length with but a small portion of the tube 60 extending externally of the tank, valve means on the upper portion of the tube externally of the tank for regulating discharge of tank contents therethrough, and a dome-like cap of imperforate construction having a removable sealed connection at the top of the tank

car and containing therein the upper portion of the tube and its valve when the tube is lowered into the tank car and surrounding and sealing therein the stuffing box connection whereby to prevent leakage of contents at 70 the connection of the stuffing box and the tube with the tank car.
